UNITED STATES PATENT OFFICE.

PETER KORDT, OF HAMBURG, GERMANY.

SHUTTLE-CARRIER MECHANISM FOR NET-MAKING MACHINES.

1,099,057.

Specification of Letters Patent.

Patented June 2, 1914.

Application filed December 14, 1912. Serial No. 736,828.

To all whom it may concern:

Be it known that I, PETER KORDT, a subject of the King of Prussia, residing at the city of Hamburg, in the State of Hamburg, 5 German Empire, have invented certain new and useful Improvements in Shuttle-Carrier Mechanism for Net-Making Machines, of which the following is a specification.

This invention has for its object to produce an improved shuttle-carrier mechanism for net-making machines of the Jouannin type whereby the movements of the shuttle-carrier and the parts coöperating therewith are shortened and modified in such a 15 manner as to improve considerably the working of the machine and simplify its construction.

In existing net-making machines the shuttle-carrier usually moves to-and-fro only 20 along a horizontal and comparatively long path, and consequently those machines can be driven only at a comparatively slow speed, and yet it has been found impossible to work such machines without vibration.

Now according to the present invention the to-and-fro movement of the shuttle-carrier is shortened by more than half, and it also receives a partial rotation for the purpose of bringing the points of the shuttles to the 30 grippers. By this means the further advantage is attained that compared with existing machines the grippers also need only make a considerably shorter movement for the purpose of delivering the gripped thread to the points of the shuttles. These improvements have the effect of rendering the working of the machine steadier and more uniform, and of enabling the machine to be driven at a considerably higher 35 speed. Further the complicated motion-transmitting devices (such as elliptic wheels and the like) employed with the object of preventing vibration and shock, may be dispensed with because the improved mode of 40 operating the machine renders the latter practically free from vibration.

One manner of carrying out this invention is illustrated by way of example in the accompanying drawings in which:—

50 Figure 1 shows the parts in the positions they occupy at the beginning of the movement of the shuttle. Fig. 2 shows the parts in their positions when the upper threads are being drawn in; Fig. 3 shows the parts 55 in their positions when the upper loops are

being delivered by the grippers to the shuttles.

The carriage *a* for the rotary shuttle-carrier *b* receives a short to-and-fro movement from the connecting rod *c*. The shuttle-carrier *b* is connected to a toothed sector *d* which is adapted to roll over a rack *e* in the longitudinal movement of the carriage *a*, and thereby cause the shuttle-carrier *b* with the shuttle *f* to rotate. The gripper holder *g* is caused by any suitable means to move horizontally in such a manner as to bring the gripped thread to the point of the shuttle. In the example the gripper holder is shown suspended in a pendulating manner. 70 The comb *h* has the usual movements.

The accompanying drawings illustrate the several positions of the carriage *a* and shuttle *f*. As the carriage *a* moves back, the point of the shuttle is gradually rotated upward in such a manner as to be brought nearer to the grippers, so that the latter need make only a correspondingly reduced movement. 75

Any suitable means may be employed instead of the rack and sector gear. 80

I claim:

1. In a net making machine, the combination of a main frame, of a carriage reciprocating in a straight line on the frame, a shuttle carrier mounted on said carriage, shuttle carrier operating means including a rack and segment, and means connected to the carriage for reciprocating same and effecting operation of the shuttle carrier operating means. 85 90

2. In a net making machine, the combination with the main frame, of a carriage movably mounted thereon, means for operating said movable carriage, a shuttle carrier mounted on said carriage, a rack bar on said frame, and means between the shuttle carrier and the rack bar adapted to operate the shuttle carrier, said means comprising a toothed sector engaging said rack bar and fastened to said shuttle carrier, whereby a movement of the movable carriage will operate the shuttle carrier. 95 100

In testimony whereof I affix my signature in presence of two witnesses.

PETER KORDT.
